UNITED STATES PATENT OFFICE

2,049,049

TOOL

Clarence O. Carlson, East Cleveland, Ohio, assignor to The American Steel and Wire Company of New Jersey, a corporation of New Jersey

Application December 29, 1934, Serial No. 759,783

2 Claims. (Cl. 81—9.1)

This invention relates to tools, and more particularly to those such as are used for applying fastener elements to unite the overlapping ends of box straps and the like, although not limited thereto.

In a co-pending application entitled "Fastener", filed December 29, 1933 and bearing Serial No. 704,561, I have disclosed a novel fastener element for uniting the ends of overlapped tying elements, and particularly box straps and the like, in such manner as to positively prevent their relative movement. The novel fastener element of this co-pending application comprises a substantially U-shaped blank which provides downwardly extending legs. This U-shaped blank has a plurality of inwardly extending apertures from both of its longitudinal edges, the axes of the bends of the legs intersecting the substantial mid-portions of the apertures. The function of this fastener element is to embrace with its downwardly extending legs the overlapped ends of a tying element of the type referred to, and to permit the upsetting of the material of the latter through the apertures, causing lugs to be sheared inwardly from its edges, and thus made to interlock with the side edges thereof.

In my Patent No. 1,986,711, dated January 1, 1935, entitled "Tool for applying fastener element", filed December 29, 1933 and bearing Serial No. 704,560, I have disclosed a novel tool to perform the operation previously mentioned, the present application being an improvement thereon.

It is among the objects of the present invention to provide a novel tool, particularly adaptable for applying a fastener element of the type referred to, which will be cheap and easy to manufacture, operable with considerable speed, and at the expenditure of but little effort.

This and further objects will be apparent after referring to the drawings, in which:

Figure 1 is a side elevation of the device of the invention.

Figure 2 is a perspective of the fastener element which the device of the invention is intended to apply.

Figure 3 is a sectional end view of the fastener element as completely applied to the overlapped ends of a box strap.

Figure 4 is a sectional elevation of the device at the same stage of operation as the elevation of Figure 1.

Figure 5 is a view similar to Figure 4 but showing the device in another stage of operation.

Figure 6 is a sectional view on the line VI—VI of Figure 5.

Figure 7 is a sectional view on the line VII—VII of Figure 6.

Figure 8 is a sectional view on the line VIII—VIII of Figure 6.

Referring more particularly to the drawings, the numerals 2 and 3 designate a pair of plates which form a housing for the various elements of the device of the invention. The plates 2 and 3 are each provided at one end with an inwardly extending boss, as at 4 and 5, respectively, which are apertured in alignment, as at 6, to receive a bolt 7. The bolt 7 carries a nut 8 for holding the plates 2 and 3 in assembled relationship, it being noted that the adjacent ends of the bosses 4 and 5 are spaced apart, as at 9, to accommodate an element to be later described.

The other ends of the plates 2 and 3 are provided with a pair of aligned apertures 12, in each of which a stud 13 is disposed. The studs 13 are maintained in position by means of nuts 14 on their ends. A lever 15 is pivoted on each of the studs 13, as shown at 16, and each carries an upward extension 17. The other and lower end of each of the levers 15 is extended inwardly at right angles, as shown at 18, and provided slightly thereabove with a recess 19. A plurality of recesses 19^a are provided in the upper surfaces of the inward extensions 18 on the lower ends of the pivoted levers 15, for a purpose to be later described.

A die 20 is disposed in each of the recesses 19, and provided with a plurality of inwardly extending lugs 21. The lower adjacent surfaces of the dies 20 are beveled, together with the inwardly extending lugs 21, as shown at 22. The side walls of the lower ends of the levers 15 are apertured to open into the recesses 19, as shown at 23. A capscrew 24 is disposed in each of the apertures 23 with its threaded extremity in a screw-threaded recess 25 in each of the dies 20, thus enabling the adjustable movement of the latter.

The lower edges of the plates 2 and 3 are provided with screw-threaded recesses 26. A magnetized guide block 27 is secured to these edges of the plates 2 and 3 by cap-screws 28 which extend therethrough, as at 29, to engage the screw-threaded recesses 26. The guide block 27 is provided on its side edges with a plurality of recesses 30 to receive the inwardly extending lugs 21 of the dies 20.

A pair of extended levers 31 are pivoted, as at 32, to the extremities of the upward extensions 17 of the levers 15. It is through these levers

31 that the elements of the device of the invention are operated. One of the levers 31 carries offset from its pivoted extremity a pair of arms 35, while the other lever carries offset from its 5 pivoted extremity a pair of arms 36, which are nested within and pivotally connected thereto by a pin 37.

A guide bar 38 is supported within the housing formed of the plates 2 and 3 by having its 10 upper end 39 held between the adjacent ends 9 of the bosses 4 and 5, and its lower end 40 apertured, as at 41, to receive the studs 13. To permit this disposition the pivoted levers 15 are recessed, for clearance, as at 42.

15 The guide bar 38 is slotted, as at 43, adjacent its upper end 39 to receive, for sliding movement, a collar 44 in which the pin 37 is journaled.

The magnetized block 27 has on each end downwardly extending legs 45 beveled on their 20 lower adjacent surfaces, as at 46. This provides a guide for placing the tool over box straps. The lower surface of the block 27 is recessed, as at 47, to permit the longitudinal placement of a substantially U-shaped fastener 50.

25 In operation, a box strap is made to embrace an article and its ends, as shown at 55 and 56 in Figure 2, are arranged in overlapped relationship. A U-shaped fastener element 50 is placed on the magnetized block 27 in the recess 47 and 30 between the inward extensions 18 of the levers 15. This alines the fastener 50 into longitudinal and transverse position for placement of itself and the tool over the box strap elements. At this stage of the operation, the levers 31 are in 35 the position indicated in Figures 1 and 4. The levers 31 are moved together, which permits their pivoted arms 35 and 36 to move the pin 37 downwardly in the slot 43 of the guide bar 38. This movement forces the upward extensions 17 of 40 the levers 15 apart, thus bringing the inward extensions 18 on the lower extremities thereof into registration with and extending through the recesses 30 in the guide block 27. This movement enables the inwardly extending lugs 18 to 45 engage the downwardly extending legs 51 of the fastener element 50 and to bend the same inwardly into intimate contact with the lower surface of the lower overlapped end 55 of the box strap.

50 As the lower extremities of the pivoted levers 15 are moved inwardly, the dies 20 in the recesses 19 are likewise made to register with the recesses 30 in the guide block 27 and permit their beveled lower adjacent surfaces to engage the portions 55 of the overlapped end 55 of the box strap which is exposed through the apertures 52. The continued movement of these beveled surfaces 22 of the dies 20 causes the bending and partial shearing of the side edges of the overlapped ends 55 60 and 56 of the box strap. These sheared portions, which are indicated at 55^a and 56^a in Figure 3, engage the side edges of the aperture 52 of the U-shaped fastener element 50 and positively prevent relative movement between the 65 same and the ends of the strap.

It will be noted in Figures 4 and 5 that the plurality of recesses 19^a in the upper surfaces of

the inward projections 18 on the lower ends of the pivoted levers 15 will permit sufficient clearance to allow the sheared portions 55^a and 56^a of the box strap to be depressed below the lower surface of the assembled fastener element 50.

After the applying operation is complete, the levers 31 are moved apart to their original positions, as shown in Figure 1, preparatory to a repetition thereof.

It is particularly important that the edges of 10 the overlapped portions 55 and 56 of the box strap be sheared (as at 55^a and 56^a) to the same depth on both sides. In order to do this, the dies 20 must be equidistant from the center line of the device at all stages of its operation. This 15 is rendered possible by pivotally connecting together the levers 31 with the pin 37, which is maintained in slidable relationship by means of the collar 44 in the slot 43 of the guide bar 38.

While I have shown and described one specific 20 embodiment of my invention, it will be understood that I do not wish to be limited exactly thereto, since various modifications may be made without departing from the scope of my invention, as defined in the following claims. 25

I claim:

1. A device for applying an apertured and substantially U-shaped fastener element comprising, in combination, a housing, a pair of jaw members pivotally mounted on said housing, a 30 guide block disposed between said pair of pivoted jaw members, said guide block being constructed and arranged to receive and hold said substantially U-shaped fastener element and having apertures which aline with the apertures of the 35 latter, means on said pivoted jaw members for contacting said substantially U-shaped fastener element intermediate its apertures and bending it to tightly embrace the object to which it is to be applied, and a die element secured to each of 40 said pivoted jaws, said die elements being constructed and arranged to partially shear portions of said object through the alined apertures in said guide block and said substantially U-shaped fastener element. 45

2. A device for applying an apertured and substantially U-shaped fastener element comprising, in combination, a housing, a pair of jaw members pivotally mounted on said housing, a magnetized guide block disposed between said 50 pair of pivoted jaw members, said guide block being constructed and arranged to receive and hold said substantially U-shaped fastener element and having apertures which aline with the apertures of the latter, means on said pivoted jaw 55 members for contacting said substantially U-shaped fastener element intermediate its apertures and bending it to tightly embrace the object to which it is to be applied, and an adjustable die element secured to each of said pivoted 60 jaws, said die elements being constructed and arranged to partially shear portions of said object through the alined apertures in said guide block and said substantially U-shaped fastener element. 65

CLARENCE O. CARLSON.
